COIL BINDING MACHINE

Penrose E. Chapman, St. Louis, Mo.

Substituted for abandoned application Serial No.
48,200, November 4, 1935. This application De-
cember 3, 1936, Serial No. 114,091

1 Claim. (Cl. 164—47)

This application is a substitute application for application No. 48,200, filed November 4, 1935, which was unintentionally abandoned and which was a division of my application No. 519,651, filed 5 March 2, 1931, now Patent No. 2,052,764 of Sept. 1, 1936.

In the drawings Figure 1 is a perspective of the coil binding machine.

Figure 2 is a plan of said coil binding machine. 10 Figure 3 is a plan detail of the binding material guides, feeding elements, actuating cam and cut-off.

Figure 4 is a side elevation of the same subject showing asymmetrical cut-off actuating 15 crank.

Figure 5 is a section through the binding material guides and cross head showing the cam followers for actuating the gripping fingers.

Figure 6 is an end elevation of the cut-off 20 mechanism, follower, and actuating cam.

Figure 7 is a detail of the feeding fingers 137 to 138'.

As coils wound on forms without insertions or 25 spools will spring apart as soon as released, it is necessary to tie or bind them in some manner before they are removed from the winding forms.

For binding the coils I may use any elongated 30 material such as soft metal, cloth or paper and some adhesive gum. For brevity I will use the word paper to include all such materials.

As changes in proportions and functions will 35 enable my invention to use any such binding material and as gummed paper requires possibly the greatest number of functions I am disclosing my invention with a machine proportioned to use it.

After the coils are wound on any winding element particularly those disclosed in the said patent, such as spindle 58, jig 101, etc., I accomplish the object of binding the coils as follows:

The paper 150 is guided into papering elements by the guides 130 and 130', Figures 1, 2, 3 to 6 inclusive.

A crosshead 131 slides in the grooves 132—133 (Figs. 5 and 6) and is actuated through its follower roller 134 by cam 135 that is mounted in any suitable manner, as upon drum 136 carried by a cam shaft. This crosshead 131 carries paper gripping fingers 137, 138, 137' and 138' (Figures 3, 4, 5 and 7). I prefer to carry one element of these gripping fingers 137 and 138 on a tube 139 attached to said crosshead 131 and the other one to the rod 140 passing through said tube 139. To actuate these gripping fingers 137 to 138' I supply crank and roller cam follower

141—142 so placed as to contact with cam surface 145. Connecting rod 143 couples crank 144 to crank 141 to actuate upper gripper fingers 137.

As the gripper fingers 137 to 138' recede they open up, pass over the end of the paper 150 and go into the notches 130" in the end of the paper guides 130 and 130', gripping the end of the paper 150 which is maintained at this point, pulling the paper out, and when the wound coil C comes to rest in the rear position of the turret 21, 10 carry the paper past the coil C and into position to be folded thereover. The fingers 137 to 138' release the paper 150 at the proper time under the influence of one of the cam faces 145.

When the proper length of paper has been fed 15 forward as just described the paper feeding elements 130 to 140 dwell for a moment while the paper is cut off.

For cutting off the paper I find it convenient to place two pair of shears 151—152 and 20 151'—152' one in front of each of the paper guides 130 and 130'. I prefer to form the corresponding blades for each chute as a part of a frame such as is shown in Figure 6. On these knife frames I form trunnions 151" and 152" for 25 their actuation. It is necessary to actuate all knives 151 to 152' in order that when open they will recede sufficiently to clear the paper gripping fingers 137 to 138'.

The knives and frames I support by any suitable framed work 153, 154, situated at the delivering end of the paper guides 130 and 130' and prefer to actuate these knives through connecting rods 155 and 156 by the bell-crank member having unequal arms 157 and 158 which are connected to the trunnions 151" and 152" on said knife frames.

In order that the end of the paper 150 be not 30 displaced, bent, kinked or otherwise damaged, it is necessary that one of the knives proceed to the normal plane of the paper and dwell while the other knife continues on its course cutting the paper as it proceeds against the now stationary blade.

To accomplish this end I use said unequal 45 crank arms, connecting the blades 152 and 152' to the short crank arms so that its motion will be negligible as the crank arms passes over the dead center. The other blade 151 and 151' is connected to the longer crank arms which is so 50 phased that said knives 151 and 151' are in motion after the knives 152 and 152' have come to rest.

These cut-off knives are actuated through the rocker shaft 159 crank 160 and its follower roller 55

161 by the cam 162 secured to the cam shaft 50.
I wish to claim:

In a coil binding device, the combination of a
binding material feed, with cut-off shears which
5 has its knives longitudinally moving in fixed par-
allel planes, both knives actuated by crank arms

of unequal length mounted on a common shaft
so proportioned and phased that one knife will
proceed to the plane of the material and dwell at
an approximately fixed position while the other
knife cuts said material off against it. 5

PENROSE E. CHAPMAN.
